SUPPORT FOR THE GUN-CARRIAGES OF RAILWAY-GUNS ON TURNTABLES.

1,360,514.

Specification of Letters Patent. Patented Nov. 30, 1920.

Application filed September 4, 1920. Serial No. 408,380.

To all whom it may concern:

Be it known that I, FRITZ FINCKH, residing at Essen, Germany, a citizen of the German Republic, have invented a certain 5 new and useful Improvement in Supports for the Gun-Carriages of Railway-Guns on Turntables, of which the following is a specification.

The object of the invention is to provide 10 supporting means for the gun carriage mountings of railway guns upon a turn-table, which render it possible to prepare the gun, which is mounted on the turn-table, rapidly ready for firing.

15 The invention will be described with reference to the accompanying drawings in which—

Figure 1 shows the turn-table and the gun carriage, partly in section and partly in side 20 elevation,

Fig. 2 the plan view of Fig. 1,

Fig. 3 a section 3—3 of Fig. 2 and

25 Figs. 4—6 correspond to Figs 1—3, with the turn-table and the gun in their firing position.

The turn-table bridge A supported on ball 30 bearings a^1 on a track B comprises a pair of girders a^2 , a^3 intersecting each other at right angles, between which girders a^2 rails C are laid, which in the position of the turn-table ready for receiving the carriage, form a continuation of the rails C^1 which lead to the turn-table. The reciprocal distance of 35 the girders a^2 is so chosen, that the normal clearance gage of the railway, shown in Fig. 3 with dotted lines, is maintained. The distance between the turntable supports a^3 is less; and corresponds to the distance between the main supports D of the gun carriage.

40 The carriage rests upon two bogies D^1 and D^2 . The cradle E^1 , which carries the gun barrel E is fixed to the main girders of the carriage by means of horizontal trunnions e^2 in such a way that, when fired at its 45 highest elevation, the breech end of the gun extends at the end of the recoil to beneath the upper edge of the rails C (see the position of the recoil marked by dotted lines in Fig. 4). The breech end of the gun barrel 50 then enters a gap a^4 in the turntable (Figs. 2—5). In the case of heavy guns the breech end of the gun barrel is wider than the free space between the rails.

When the turn-table is in the position 55 shown in Figs. 1—3 the gun is mounted on

it in such a way that the trunnions are situated practically over the middle of the turn-table. The bogies D^1 D^2 then rest on the rails C^1 on both sides of the gap in the turn-table. The turn-table is then swung 60 at an angle of 90° in the direction of the arrow x (Fig. 2) into the position shown in Figs. 4—6, so that the girders a^3 of the turn-table come under the supports D of the gun carriage. Then after the gun carriage 65 has been lifted off them by means of lifting jacks or the like the bogies D^1 D^2 are moved to the side and then the gun carriage is lowered, so that its supports D rest on the turn-table supports a^3 . 70

The turning of the turn-table from the receiving position to the firing position has the advantage that the gun carriage can be placed directly on to the turn-table supports a^3 ; it is, therefore not necessary to 75 attach beams or wedges for supporting the gun carriage to the turn-table supports a^2 , on which, owing to their distance apart, the gun carriage could only rest indirectly. Further, by turning the turn-table the rails 80 C are moved in the simplest manner out of the way of the recoiling breech end of the gun barrel. By this means the tedious removing of the rails C and their supports is avoided, so that for this reason the gun, 85 when mounted on the turn-table, is very rapidly ready for firing.

Claims:

1. A device of the class described which comprises a turntable, a pair of girders 90 forming a part of the turntable, a line of rails carried by said turntable and between said pair of girders, a second pair of girders disposed transversely of said line of rails, an opening between said second pair of 95 girders, said line of rails enabling a gun carriage of railway guns to be positioned over said turntable.

2. A device of the class described which comprises a turntable, a line of tracks on 100 said turntable, a pair of supporting members mounted on said turntable and transversely of said line of tracks, all of which are so arranged that a railway gun may be run across said turntable and thereafter the 105 gun mounted on said supporting members.

3. A device of the class described comprising a turntable, a line of rails carried by said turntable, two pair of main girders forming a part of said turntable, one pair 110

of said girders being disposed at right angles to the line of rails, said line of rails enabling a gun carriage of railway guns to be positioned over said turntable, the distance between said transversely disposed girders being the same as the distance between the main supports of the gun carriage, whereby the turntable may be rotated to position the transversely disposed girder 10 under the main supports of the gun car-

riage, substantially as and for the purpose set forth.

The foregoing specification signed at Essen, Germany, this 11th day of June, 1920.

FRITZ FINCKH.
